UNITED STATES PATENT OFFICE.

WILLIAM HEBARD, OF WINNEMUCCA, NEVADA.

CENTRIFUGAL PUMP.

Application filed January 3, 1922. Serial No. 526,784.

To all whom it may concern:

Be it known that I, WILLIAM HEBARD, a citizen of the United States, residing at Winnemucca, in the county of Humboldt and State of Nevada, have invented new and useful Improvements in Centrifugal Pumps, of which the following is a specification.

This invention relates to water pumps for the circulation systems of internal combustion engines, and particularly to an auxiliary pump which may be readily intercalated in a system which is normally thermo-siphonic, in order to increase the rapidity of flow of the cooling medium therethrough and, in consequence, to enhance the cooling efficiency of the radiator forming a part of said system.

One of the objects of the invention is to provide a circulation pump as an integral part of the upper hose connection which is usually bolted to the forward part of the cylinder head, and connects with the hose leading to the radiator.

Another object of the invention is the provision in the cooling system of an internal combustion engine of a pump having a centrifugally functioning impeller, and a by-pass from the delivery to the discharge conduits leading to and from said impeller, whereby thermo-siphonic movement of the cooling medium may continue without interruption should the impeller become stalled through slippage of the belt or through other causes.

Another object of the invention is the construction of a pump in which the discharge and delivery conduits are arranged within the casting in such manner as to permit a minimum thickness of the casting, enabling it to be accommodated within the limited space between the engine block and cooling fan.

Still another object of the invention is the construction by which the drive pulley for the pump surrounds the stuffing gland for the shaft of the pump impeller, whereby compactness of the device is secured and the drive pulley positioned in the plane of the fan pulley.

A still further object of the invention is the arrangement of the pump driving means in operative relation to the fan pulley and crank shaft pulley by means of a single belt passing around all three elements, said belt being tightened relative to the driving

means of the pump impeller by adjusting the position of the fan pulley.

With the above and other objects in view, my invention consists in the improved water pumps for the circulation systems of internal combustion engines illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:—

Figure 1 is a side elevation, more or less diagrammatic in character, showing the cooling system of an automobile engine with my improved centrifugal pump applied thereto.

Figure 2 is a front elevation of the pump.

Figure 3 is a sectional view taken along the line 3—3 of Figure 2.

Figure 4 is a plan view of the device shown in Figure 2.

Figure 5 is a cross section through a drive pulley and part of the casing of the pump, part of the latter being broken away.

Figure 6 is a cross section taken along the line 6—6 of Figure 5 showing the pump impeller.

Figure 7 is a front elevation, diagrammatic in character, showing the relative position of the pump, fan pulley and crank shaft pulley in operative relation to an internal combustion engine.

Referring in detail to the several figures the numeral 1 represents the water jacketed cylinder block of an internal combustion engine, including the cylinder head 2 which is connected to the radiator 3 by means of the water conduits 4 and 5.

The cooling fan is represented at 7 which is mounted on a shaft 8 carried by an arm 9, the latter being swingably supported upon a bolt 10 secured to the front of the casing 11 forming part of the cylinder block of the automobile engine.

The crank shaft 12 of the engine is provided with the driving pulley 13 connected to the fan pulley 14 by means of a belt 15, through which said fan pulley is driven.

For the purpose of tightening said belt the arm 9 supporting said fan pulley may be

swung upon the bolt 10 as a pivot and may be secured in any position of adjustment by tightening said bolt.

In the ordinary thermo-siphonic cooling system the conduit 4 includes an upper hose connection bolted to the water jacket of the cylinder head by means of bolts 6 which pass through apertures 37 and 38 in said hose connection as shown in Figure 2. Between 10 the latter fitting and the radiator is clamped a piece of flexible hose 36. The space between the fan 7 and cylinder block 1 is narrow, and heretofore, it has been customary, in the construction of an auxiliary pump for 15 use in a thermo-siphonic cooling system to associate it with the hose connection 16 forming part of the conduit 5. The use of a pump at this point, however, entails an excessively long drive shaft for the pump impeller and usually a support for the same, making a cumbersome and undesirable arrangement.

By my invention I replace the upper hose coupling with a substitute upper hose coupling 35 having the pump casing 17 cast integral therewith. This substitute coupling is provided with bolt holes 37 and 38 registering with the existing bolt holes in the cylinder head 2 and with an inlet conduit 31 20 communicating at one end with the water jacket of the cylinder head and extending upwardly at the other end, forming an outlet passage 18 similar in every respect to the corresponding outlet of the original hose 25 connection so that no alteration in the structure into which it is intercalated is required, to make the substitution of the pump of the present invention for the original part. The pump casing 17, referring now to Figures 2, 30 3 and 4 is offset, to one side of the flanged portion of the upper hose coupling 35 and is provided with a suction conduit 19 which 35 opens into the central part of the chamber of said pump casing and communicates at 40 its upper end with the conduit 31.

From the peripheral portion 23 of the chamber of the pump casing extends a delivery conduit 22 which also communicates at its upper end with the conduit 21. A common 45 wall 32 separates the conduits 19 and 22 and terminates at the point where said conduits enter the conduit 31. A water impeller 21 is journalled within the pump casing 17 and, as shown in cross section in Figure 6, comprises 50 radial arms, slightly curved in the direction of the propeller shaft 25, forming between them chambers with the central portions of which the inlet conduit 19 communicates. The suction and delivery conduits constitute 55 a by-pass by means of which water is diverted 60 from the thermo-siphonic column ascending from the water jacket to the radiator of the automobile through the conduit 31 in the hose coupling, said water being thereupon 65 forcibly circulated through the circulation

system of the engine. While the device of my invention is primarily intended to normally circulate water by means of the pump, yet should said forced circulation be impaired by slippage of the belt or blocking of 70 the pump impeller through freezing or other causes, the thermo-siphonic circulation through the conduit 31 and discharge passage 18 will continue without impediment due to the presence of the idle pump parts, since the 75 latter are located in the by-pass entirely out of the path of thermo-siphonic flow.

The impeller shaft 25 is carried in bearings 26 and 26' in the opposite sides of the pump casing and extends forwardly into the 80 plane of the driving belt 15 where it is provided with a pulley 27, keyed thereto at 28, and further secured in place by means of the set screw 29. This pulley is in frictional engagement with the driving belt 15 which 85 surrounds also the crank shaft pulley 13 and the fan pulley 14 as shown in Figure 7.

The pulley 27 is deeply flanged forming a cup shaped depression in one side thereof in which is housed the stuffing gland 30 by 90 means of which the drive shaft 25 is packed against leakage.

It will be understood, particularly from Figures 3 and 4, that the conduits 18 and 19 are flattened at that portion of their length 95 which embraces the common wall 32, so that the aggregate thickness of the casing which encloses this portion of said conduits is not much in excess of the width of the outer end of the outlet passage 18. By this construction, and by the disposition of the stuffing gland 30 within the flanged pulley 27 a compact construction of pump is realized which 100 is readily accommodated in the restricted space between the fan and the engine cylinder block. 105

In the installation of my improved centrifugal pump, the same bolts are used as were utilized to hold in place the original upper hose connection. The fan belt is sufficiently 110 long to pass around the crank shaft pulley and both the pump and fan pulley as shown in Figure 7, and are tightened by swinging the arm 9, upon which the fan pulley is journalled, outwardly against the belt as 115 hereinbefore described. Should slippage of the belt occur, however, circulation of water through the cooling system will be continued thermo-siphonically through the passage 24 120 in the same manner as before the pump was 125 installed.

Having described my invention what I claim as new and desire to secure by Letters Patent, is: —

1. A water circulating device for the cooling systems of automobile power plants, consisting of a coupling adapted to be inserted between the engine and radiator including a permanently open conduit affording communication between the water space 130

of the engine and the radiator to permit constant thermo-siphonic flow therethrough, said coupling being formed with a by-pass communicating at both ends with said conduit, and a pump in said by-pass.

2. A water circulating device for the cooling systems of automobile power plants consisting of a coupling adapted to be inserted between the engine and radiator, including
10 a permanently open conduit which affords communication between the water space of the engine and the radiator, to permit constant thermo-siphonic flow therethrough,

said coupling being formed with a chamber off-set from said conduit and communicating therewith, a flat partition wall intersecting said chamber for a part of its length, forming a by-pass communicating with said conduit, and a pump in said by-pass.

In testimony whereof I have hereunto set 20 my hand in presence of two subscribing witnesses.

WILLIAM HEBARD.
